SHOE UPPER

Filed July 26, 1927

INVENTOR.
JOHN EMERSON SCOTT
BY.

H. A. Dreckman
ATTORNEY

UNITED STATES PATENT OFFICE.

JOHN EMERSON SCOTT, OF LONG BEACH, CALIFORNIA.

SHOE UPPER.

Application filed July 26, 1927. Serial No. 208,469.

This application is a continuation in part of my co-pending application, Serial Number 149,847, filed November 22, 1926.

An object of my invention is to provide a seamless shoe upper which can be entirely completed before it is lasted and the sole placed thereon.

Another object is to provide a shoe upper in which the stitching machine can extend either from the top or the bottom thus making it possible to stitch any portion thereof.

Still another object is to provide a seamless shoe upper provided with a retainer at the rear thereof, or any other portion, or all over the back of the upper.

An advantage of my upper resides in the smooth creaseless surface thereof thus providing a neater, more effective, and better looking shoe.

20 Other objects, advantages, and features of invention may appear from the accompanying drawing, the subjoined detailed description, and the appended claims.

In the drawing:

25 Fig. 1 is a plan view of the leather piece from which the seamless upper or lining is formed.

Fig. 2 is a side elevation of the upper after having been formed.

30 Fig. 3 is a side elevation of the upper with the cuts shown therein to form the tongue.

Fig. 4 is a view similar to Fig. 3 but with the upper shown wrong side out.

Fig. 5 is a side elevation with parts broken away of the shoe upper.

Fig. 6 is a bottom plan view of the assembled shoe upper.

Fig. 7 is a side elevation of the completed shoe.

40 Referring more particularly to the drawing:

An elliptical piece of material 1 may be leather, cloth, fabric, or any other suitable material is placed in a machine and is formed into the shape shown in Fig. 2. This process is usual and well-known in the art. During this step of forming the upper no creases or wrinkles are formed in the upper portion 2, thereof. The lower portion of the upper may be slightly creased or wrinkled due to the effect of the die or form. In order that the material may retain its shape during the further steps in the manufacture of the complete shoe, I secure a retainer strip 3 to the material. This strip may cover the entire back

of the shoe or any other portion thereof where it is necessary or expedient to so hold the leather that it will not stretch out of shape. This strip may be cemented to the material, stitched, or otherwise secured thereto.

It is obvious that this strip may be formed in various ways. A single narrow strip may be utilized, or a plurality of strips, or a single side strip may be employed if it is found desirable and necessary. The upper is preferably formed inside-out up to this point in its manufacture or may be formed right-side-out, and the backing is secured in place after which the upper is turned right-side-out and then cut along the line 4 to provide the top opening of the upper through which the foot is to be inserted. The cut may be made before or after the upper is turned. A lining may now be formed by any well-known process, or according to my process which is described in my co-pending application, Serial No. 208,470, filed July 26, 1927.

To keep the upper from stretching the retainer 3 may be stitched along the lower edge thereof, as at 5, or may be sewed in place by the stitching used to hold the upper together, or by the stitching securing the overlays, or the like, thus holding the upper in shape.

In Fig. 4 the tongue portion 6 has been cut off as is necessary when an oxford is formed, whereas, in Fig. 3 it is left long as is necessary when a high shoe upper is formed.

After the upper 1 and lining 7 have both been separately formed the lining is placed inside of the upper and the two are stitched together adjacent the tops thereof and around the tongue 6, as shown in 8, and such other stitching as may be necessary to complete the upper. That is, the upper and lining are secured together after both have been removed from their creasing and the bottom and top thereof are open so that the stitching machine can readily extend inside of the upper, and various overlays, cut-outs, or the like, may be stitched in position with a minimum amount of effort and labor. After the upper has been formed in the manner stated, the shoe may be lasted or made up by any of the well-known methods, such as welt, McKay, turned, or stitched down. The completed shoe is shown at 9.

If it is found necessary the retainer strip 3 may be cut away at the heel or elsewhere, so that the upper may take the shape of the last, or if found expedient after the upper has

been formed the retainer may be entirely removed. However, the portions not cut away will prevent the remaining parts of the upper from stretching. That is, the retainer is practically non-stretchable, while the leather, or the like, forming the upper will readily give to conform to the shape of the last. Therefore, the retainer is cut at the desired point, or points, and the leather will then readily 10 extend to form the curve of the heel, or any other extended or curved portion of the last.

It is evident that while I have described a seamless upper I may employ a pieced upper if it is found desirable.

15 If it is found necessary I may insert a step in my method of forming uppers after said upper has been formed over the die, this step consisting of applying heat to the upper so that it will be contracted about the die or 20 form to conform exactly to the shape thereof. This application of heat may be through ironing or a similar process, and the ironing occurs while the upper is held in shape on the

form. After the ironing step the retainer is placed on the upper as previously stated. 25

Having described my invention, I claim:

1. In a shoe comprising a seamless upper, a retainer strip secured to the upper, a seamless lining, and a retainer strip secured to the lining, said lining and upper being secured together. 30

2. In a shoe comprising a seamless upper, a retainer strip secured to the upper, a seamless lining, and a retainer strip secured to the lining, said lining and upper being secured together with the bottom left open. 35

3. In a shoe comprising a seamless upper, and a retainer strip secured to said upper, said retainer strip being cut away at points to permit the upper to conform to the shape of the 40 last, said retainer strip preventing the stretching of the upper except at points where the strip is cut away.

In testimony whereof, I affix my signature.

JOHN EMERSON SCOTT.
